(57) **CLAIM**

The ornamental design for a torso-support apparatus, as shown and described.

DESCRIPTION

This application relates to U.S. Ser. No. 29/412,784, filed concurrently herewith both naming Lewis Sharps as the inventor, and entitled "Torso-Support Apparatus".

FIG. 1 is a top-perspective-left-side view of an example torso-support apparatus;

FIG. 2 is a rear view thereof;

FIG. 3 is a front view thereof;

FIG. 4 is a lift-side view thereof;

FIG. 5 is a right-side view thereof;

FIG. 6 is a bottom view thereof; and,

FIG. 7 is a top view thereof.

The broken lines showing the torso-support apparatus, or portion thereof, are not a part of the claimed design.
